[57] CLAIM

The ornamental design for motorcycle combined radio and speaker support, as shown.

DESCRIPTION

FIG. 1 is a front elevational view of a motorcycle combined radio and speaker support showing my new design, with the broken line structure being environmental and forming no part of the claimed design;

FIG. 2 is a front elevational view of the radio support alone, with broken line structure being environmental;

FIG. 3 is a top plan view thereof;

FIG. 4 is a bottom plan view thereof;

FIG. 5 is a left side elevational view thereof;

FIG. 6 is a right side elevational view thereof;

FIG. 7 is a rear elevational view thereof;

FIG. 8 is a front elevational view of a speaker;

FIG. 9 is a left side elevational view thereof;

FIG. 10 is a right side elevational view with environmental broken line structure;

FIG. 11 is a top plan view thereof;

FIG. 12 is a bottom view plan thereof; and,

FIG. 13 is a rear elevational view.
